UNITED STATES PATENT OFFICE.

JOHN PAUL SCHIBER, OF EDWARDSVILLE, ILLINOIS.

STAMP-AFFIXING MACHINE.

1,267,462.

Specification of Letters Patent. Patented May 28, 1918.

Application filed June 22, 1917. Serial No. 176,389.

To all whom it may concern:

Be it known that I, JOHN PAUL SCHIBER, a citizen of the United States, residing at Edwardsville, in the county of Madison and State of Illinois, have invented certain new and useful Improvements in Stamp-Affixing Machines; and I do hereby declare the following to be a full, clear, and exact description of the invention, such as will 5 enable others skilled in the art to which it appertains to make and use the same.

This invention relates to a stamp affixing machine and has for one of its objects the provision of a device of this character, 15 whereby a stamp may be delivered and affixed to a letter, postal or the like in one single operation of the device.

Another object of this invention is the provision of means to feed and sever a 20 stamp from a roll of stamps on to a letter, postal or the like, in a single operation of the device.

A further object of this invention is to provide automatic means for applying moisture to the stamp prior to being deposited 25 on the letter, postal or the like.

A further object of this invention is the provision of means to compress the stamp on the letter, postal or the like to cause the 30 same to become thoroughly affixed thereto.

A still further object of this invention is the provision of a stamp affixing machine of the above stated character, which shall be simple, durable and efficient, and which 35 may be manufactured and sold at a comparatively low cost.

With these and other objects in view as will become more apparent as the description proceeds, the invention consists in certain 40 novel features of construction, combination and arrangement of parts as will be hereinafter more fully described and claimed.

For a complete understanding of my invention, reference is to be had to the following description and accompanying drawings, in which:

Figure 1 is a side elevation of a stamp affixing machine constructed in accordance 45 with my invention.

Fig. 2 is a longitudinal sectional view of the same,

Fig. 3 is a vertical sectional view illustrating the means of applying moisture to the stamps,

Fig. 4 is a similar view illustrating the means for feeding the stamp and depositing the same upon a letter or the like,

Fig. 5 is a transverse sectional view illustrating a recorder,

Fig. 6 is a fragmentary elevational view drawn upon an enlarged scale of the feeding and depositing mechanism for the stamp,

Fig. 7 is a fragmentary sectional view 65 taken on the line 7—7 of Fig. 6.

Referring, in detail to the drawings, the numeral 1 indicates a base having secured thereto, rear vertical supporting members 2, to which are pivoted operating levers 3, 70 as shown at 4. The front and rear ends of the operating members 3 are connected by rods 5. The front rod 5 has journaled thereon, handles 6, which have secured to their upper ends, the hand grips 7. The lower ends of the handles 6 have journaled therebetween, a roller 8, for causing the stamps to be compressed upon the letters and become thoroughly affixed thereto by oscillating the handles 6, causing the roller 80 8 to run back and forth over the stamp when applied to the letter. The handles are normally supported in an inclined position as shown in Figs. 1 and 2 by a coiled spring 9, which has one end connected to 85 the handles and its opposite end connected to the operating members 3.

Front vertical supporting members 10 are secured to the base 1 and are connected to the vertical supporting members 2 by side 90 members 11. Substantially L-shaped arms 12 are formed upon the vertical members 10 and have one of their arm portions provided with elongated slots 13 for the purpose of receiving the rod 5, which projects beyond 95 each of the operating members 3 so as to guide the front ends of the operating members as they are rocked upon their pivots 4.

A shaft 14 is journaled to the vertical supporting members 2 and has secured thereon, a roller 15 for the purpose of supporting stamps 16, which are wound thereon, in a single strip. The strip of stamps passes from the roller 15 under a roller 17

carried by the side members 11 and has the forward end of the first stamp disposed under a block 18 carried by the side members 11. A feeding roller 19 is journaled in the side members 11 and directly under the roller 17 and has formed thereon, a plurality of teeth 20 for engagement with the strip of stamps to feed the same off of the roller 15 upon rotation thereof. A gear 21 is secured to the roller 19 and engages a rack bar 22, which is pivoted to one of the operating members 3, whereby upon pushing downwardly upon the handles 6, the operating members 3 rock upon their pivots, causing the rack bar 22 to move downwardly, rotating the roller 19, causing the strip of stamps to be fed off of the roller 15.

The side members 11 are provided with slots 23, which form a track for a shaft 24 to travel upon, and are provided with upwardly inclined branches 25 at their rear ends for receiving the shaft 24 when in its normal position. The shaft 24 has journaled thereon, a rod 26, the forward end of which is curved as at 27 and pivoted to the heel portion of a member 28. The member 28 has mounted thereon, a lever 29. A roller 30 is journaled to the member 28 and is adapted to have the stamps fed thereto by the roller 19. A clamping member 31 is pivoted to the member 28 and has formed thereon, a lever 32 of a greater length than the lever 29. An arm 33 is pivoted to one of the side members 11 as at 34 and has pivoted to its upper end, a rod 35, which is pivoted to the upper end of the lever 32. The rod 26 has formed at one end thereof, a loop 36 to slidably receive a pin 37 upon the arm 33. A rod 38 is pivoted to the arm 33 and to a crank arm 39 carried by the gear 40. The gear 40 is journaled to a standard 50 carried by the base 1. A rack bar 51 is pivoted to the rear end of one of the operating members 3 and meshes with the gear 40, whereby upon upward movement of the rear ends of the operating members 3, the gear 40 is rotated by the rack bar 51. Upon rotation of the gear 40, the crank arm 39 moves the arm 33 forwardly upon its pivot by the rod 38, which causes the lever 32 to swing upon its pivot moving the clamping member 31 into engagement with the roller 30, which clamps the forward end of a stamp therbetween.

As the clamp 31 moves into engagement with the roller 30, the pin 37 upon the arm 33 engages the forward wall of the loop 36, causing the rod 26 to move the member 28 forwardly. As the member 28 moves forwardly, the shaft 24 moves downwardly in the branches 25 and into the slots 23, causing the clamping member 31 and roller 30 to move forwardly, carrying the stamp therewith. A stop 42 is carried by the forward ends of the side members 11 and is adapted to engage the upper end of the lever 32 when the member 28 moves forwardly to its foremost position, which rocks the clamp 31 upon its pivot, releasing the stamp, allowing the same to fall upon a letter, postal or the like placed upon the base.

A guide track 43 is carried by the base and supports the stamp and roller 30 as the same are moved forwardly by the member 28 and the clamp 31.

A knife 44 is pivoted to one of the side members 11 and is pinned transversely over the strip of stamps and has its free end normally held upwardly by a spring 45. An arm 46 is secured to one of the operating members 3, and has formed thereon, a notch 47 adapted to engage the lug 48 formed upon the knife 44, whereby upon downward movement of the members 3, the knife will be moved downwardly.

An arm 49 is pivoted to one of the side members as at 50 and has secured to its forward end, an anvil 51, which is normally disposed rearwardly of the knife 44 and below the strip of stamps. A rod 52 is pivoted to the arm 49 and extends rearwardly into engagement with the rack bar 41, which is provided with an offset portion 57, whereby upon upward movement of the rack bar 41, the rod 52 rides upon the offset portion 57 causing the same to move forwardly and moving the anvil 51 forwardly and under the knife 44, whereby upon downward movement of the knife 44, by the arm 47, the first stamp upon the strip of stamps will be severed therefrom. This cutting operation occurring simultaneously with the clamping member 31, moving in engagement with the roller 30 to grip the forward edge or end of the stamp, and as the knife cuts the stamp from the remaining stamps of the strip, the member 28 moves forwardly carrying the stamp forwardly to a position for the same to be deposited upon a letter, postal or the like, positioned upon the base, which occurs when the lever 32 engages the stop 42, releasing the clamp 31 from engagement with the roller 30.

A track 54 is secured to one of the side members 11 and has an upwardly inclined branch 55 communicating with a horizontal branch 56. The horizontal branch 56 communicates with a downwardly extending branch 57 that communicates with a return branch 58. A shaft 59 has one end disposed within the track 54 and its opposite end has secured thereon, a brush 60, which normally depends downwardly within a receptacle 61 carried by the base. The receptacle 61 contains water or other liquid for the purpose of moistening the brush 60. An arm 62 is pivoted to the shaft 59 and to an arm 63 as shown at 64. The arm 130

63 is journaled upon the shaft 14 and has pivoted thereto, an arm 65. The arm 65 is pivoted to a crank arm 66 carried by a gear 67 and is journaled upon a standard 68 carried by the base 1. A rack bar 69 is pivoted to the rear end of one of the members 3 and meshes with the gear 67 for rotating the crank arm 66, which causes the arm 63 to rock upon its pivot. As the arm 63 rocks upon its pivot, the shaft 59 moves upwardly in the branch 55, carrying therewith, the brush 60.

A projection 70 is formed upon the shaft 59 and is adapted to engage a trip 71 carried by the track 54 when the shaft 59 moves into the horizontal branch 56 for the purpose of rotating or swinging the brush 60 upwardly so that the same will move against the adhesive side of a stamp, which is disposed downwardly. The shaft 59 passes from the branch 56 downwardly in the branch 57, causing the brush 60 to entirely moisten the adhesive side of the stamp, and as the shaft 59 reaches the lowermost point in the branch 57, the arm 63 has then been moved forwardly to its foremost point, and the crank arm 66 begins to draw upon the arm 65, which causes the shaft 59 to travel rearwardly to its normal position in the branch 58, disposing the brush 60 over the receptacle 61. As the shaft returns to its normal position as shown in Fig. 3, the extension 70 disengages the trip 71, permitting the brush to depend downwardly into the receptacle 61 to be again moistened. A resilient arm 72 is secured to one of the side members 11 and has its free end disposed so that the shaft 59 when moved forwardly upon its initial stroke, will be compelled to pass upwardly in the inclined branch 55. The brush 60 and shaft 59 reach the farther point of the branch 56 before the knife 44 severs the stamp from the remaining stamps of the strip so that the brush will have time to moisten the adhesive face of the stamp.

A suitable guard 73 is secured to the base 1 and is disposed upwardly and forwardly to prevent the brush from applying moisture to other stamps contained in the strip which is wound upon the roller 15.

In operation, a letter, postal or the like, which is to have a postage stamp applied thereon is placed upon the base 1 at a point substantially as indicated at A. The operator then presses downwardly upon the handles 6, which rocks the members 3 upon their pivots 4. The end stamp upon the strip of stamps upon the roller 15 is then gripped by the clamp 31 and is drawn forwardly by the forward movement of the member 28 and simultaneously the brush 60 applies moisture to the adhesive face thereof. As the member 28 reaches its forward position, the knife 44 moves downwardly severing the stamp from the strip of stamps. As the knife 44

severs the stamp, the lever 32 engages the stop 42, releasing the clamp 31 from engagement with the roller 30 depositing the moistened stamp upon the letter, postal or the like, positioned at the point A. The roller 8 is then in engagement with the letter, postal or the like and by oscillating the handles 6, the roller 8 passes over the stamp upon the letter, postal or the like compressing the same so that it will become thoroughly affixed to the letter, postal or the like. The operating members 3 after the stamp has been applied to the letter, postal or the like, they are returned to their normal position, as illustrated in Fig. 1 by means of a coiled spring 74.

A recorder 75 of a well known construction is mounted upon a plate 76 carried by the vertical supporting members 2 and is adapted to be actuated by a resilient arm 77 secured to one of the operating members 3, whereby upon downward movement of the operating members to operate the machine, the recorder 75 will be moved one point, indicating that one letter, postal or the like has been supplied with a stamp.

While I have shown and described the preferred embodiment of my invention, it will be understood that minor changes in construction, combination and arrangement of parts may be made without departing from the spirit and scope of the invention as claimed.

Having thus described my invention, what I claim is:

1. A stamp affixing machine comprising a frame, operating members pivoted to said frame, means supporting a strip of stamps on said frame, means actuated by the operating members to feed the stamps forwardly of the frame, means for gripping the first stamp of the strip of stamps and to move said stamp forwardly and downwardly, means applying moisture to the first stamp, means for severing said stamp from the strip of stamps, and means depositing the severed stamp on an envelop.

2. A stamp affixing machine comprising a frame, operating members pivoted to said frame, means supporting a strip of stamps on said frame, feed rollers journaled in said frame and receiving the strip of stamps, means for connecting the feed rollers with the operating members to be rotated upon movement of the operating members, means for gripping the end stamp of the strip of stamps and moving the same forwardly and downwardly, means for applying moisture to said end stamp, means severing said end stamp from the strip of stamps, and means for depositing said stamp on an envelop.

3. A stamp affixing machine comprising a frame, operating members pivoted to said frame, means supporting a strip of stamps on said frame, rollers journaled in said

frame and receiving the strip of stamps, means for gripping the end stamp of the strip of stamps, means for severing said stamp from the strip of stamps, means for 6 moving the gripping means forwardly and downwardly, means for releasing the gripping means to deposit the stamp on an envelop.

4. A stamp affixing machine comprising a frame, operating members pivoted to said frame, means supporting a strip of stamps on said frame, feed rollers receiving said stamps, means for connecting the feed rollers with the operating members, a shaft 15 slidably mounted in said frame, a rod pivoted on said shaft, a member pivoted at one end of said rod, a roller journaled to said member, a clamp pivoted to said member, a lever formed on said clamp, means for causing the clamp to grip a stamp against the roller, means connected with said rod for causing the clamp and member to move forwardly, means for engagement with the lever when moved forwardly to disengage the 25 clamp from the roller to free the stamp, and means for compressing the stamp upon a letter.

5. A stamp affixing machine comprising a frame, means supporting a strip of stamps on said frame, means for feeding said stamps forwardly of said frame, means for severing the stamps, a shaft slidably downwardly and forwardly on said frame, a rod pivoted to said shaft, a member pivoted to 30 said rod, a roller carried by said member, a clamp pivoted to said member, a lever formed on said clamp, an arm pivoted to said frame and to the rod, a rod pivoted to the lever and to the arm for causing the 35 clamp to engage the roller to grip a stamp upon movement of the arm, and means for rocking the arm upon its pivot to operate the clamp and to move the clamp and member forwardly and downwardly on the 40 frame, and a stop upon the frame to engage the lever to disengage the clamp from the roller to free the stamp.

6. A stamp affixing machine comprising a frame, means supporting a strip of stamps upon said frame, means for cutting said stamps, means for gripping and moving the stamps forwardly, a brush carried by said frame, and means for supplying said brush with moisture, means for causing said brush 50 to move upwardly and apply moisture to the stamps upon movement of the stamps forwardly, and means for releasing the stamps to deposit said stamps upon a letter.

7. A stamp affixing machine comprising a frame, means supporting a strip of stamps on said frame, a track carried by said frame, a receptacle carried by said frame and having water therein, a brush operable on said track, means for causing the brush to travel 55 upon the track to apply moisture to the

stamps as said stamps move forwardly on the frame, means cutting said stamps, and means moving the cut stamps forwardly and downwardly.

8. A stamp affixing machine comprising a frame, means supporting a strip of stamps on said frame, means for cutting said stamps, a track carried by said frame, a brush operable on said track, a receptacle carried by said frame and normally receiving said brush to apply moisture thereto, a trip carried by said track, a projection carried by said brush and adapted to engage the trip to cause said brush to move upwardly to apply moisture to the adhesive face of a stamp, and means for causing the brush to travel upon the track.

9. A stamp affixing machine comprising a frame, means supporting a strip of stamps upon said frame, a track carried by said frame, a trip on said track, a shaft slidably on said track, a brush carried by said shaft, means for causing the shaft to move on said track, a projection on the brush adapted to engage the trip to cause said brush to turn and engage the adhesive face of the first stamp of the strip of stamps as said stamps move forwardly, means cutting said stamps, means moving the cut stamps forwardly and downwardly and means applying said cut 95 stamps to letters.

10. A stamp affixing machine comprising a frame, operating members pivoted on said frame, a handle pivoted on said operating members, a roller carried by said handle, 100 means supporting stamps on said frame, means for feeding the stamps forwardly, an anvil slidably on said frame, means for connecting the anvil to the operating members to move said anvil forwardly upon the 105 downward movement of the operating members, a knife pivoted to said frame and disposed over the stamps and anvil, and means carried by the operating members for engagement with the knife to move said 110 knife downwardly to cut the stamps.

11. A stamp affixing machine comprising a frame, operating members secured to said frame, a handle pivoted to said operating members, a roller carried by said handle, 115 means supporting a strip of stamps on said frame, a moisture applying means carried by said frame and operatively connected with the operating members for applying moisture to the stamps upon movement of the operating members, a knife carried by said frame and actuated by movement of the operating members to cut the stamps, and means carried by said frame for gripping the stamps and moving the same forwardly upon the movement of the operating members.

12. A stamp affixing machine comprising a frame, means supporting stamps on said frame, a substantially rectangular track car- 120

ried by said frame, a shaft mounted on said track, a brush carried by said shaft, means causing the shaft to travel upon the track, a resilient member carried by the frame and 5 adapted to prevent the brush from moving in an incorrect direction upon the track, means for gripping the stamps and carrying said stamps forwardly and downwardly on the frame, means cutting said stamps,

and means applying the cut stamps to 10 letters.

In testimony whereof I affix my signature in presence of two witnesses.

JOHN PAUL SCHIBER.
